UNITED STATES PATENT OFFICE.

JOSEPH GOULDBOURN AND FRED RICKS, OF LEICESTER, ENGLAND, ASSIGNEES TO
UNITED SHOE MACHINERY CORPORATION, OF PATERSON, NEW JERSEY, A COR-
PORATION OF NEW JERSEY.

UPPER-SHAPING MACHINE.

Application filed August 19, 1920. Serial No. 404,634.

To all whom it may concern:

Be it known that we, JOSEPH GOULDBOURN and FRED RICKS, subjects of the King of England, residing at Leicester, Leicestershire, England, have invented certain Improvements in Upper-Shaping Machines, of which the following description, in connection with the accompanying drawings, is a specification, like reference characters on the drawings, indicating like parts in the several figures.

This invention relates to machines for use in the manufacture of boots and shoes for shaping or forming the upper materials. The invention is herein illustrated in its application to a type of machine shown and described in prior United States Letters Patent Nos. 1,156,897 and 1,190,753 granted respectively on October 19, 1915, and on July 11, 1916 upon applications of Messrs. Gouldbourn, Bates and Jerram, and Patent No. 1,247,011, granted on November 20, 1917 upon application of Fred Ricks, machines of this type being particularly adapted for molding the heel end portion of upper materials. While it is one of the objects of the invention to provide improvements in machines of this type, it is to be understood that in many of its aspects the invention is not limited to the illustrative type of machine nor restricted in utility to the shaping of the heel end portion of the upper.

An important feature of the invention resides in a novel organization affording provision for adjustment of an upper relatively to upper clamping or shaping means at an intermediate stage in the operation of the machine. As applied to a type of construction wherein the upper is shaped between inner and outer formers that are moved relatively to operative position by power driven mechanism, the invention in its illustrative embodiment provides means for bringing the machine to a stop with the upper lightly held between the formers in such manner as to permit it to be adjusted prior to the application of the full upper shaping pressure which is effected upon a subsequent starting of the machine. This organization contributes to uniformity and precision in the operation of the machine upon the work, and is of particular advantage where there is con-

siderable variation in the character of the work or where the machine is in charge of a comparatively inexperienced operator.

Another feature of the invention consists in novel means of control for wiping means whereby the margin of an upper is shaped to produce a flange adapted to be secured to a sole or insole. In the illustrative type of machine the wipers are operated by mechanism which moves in one direction to impart to them their overwiping movement and then to force them toward the inner former for compressing the margin of the upper and which moves in the opposite direction to withdraw the wipers from the overwiping plane and to return them to their starting position. The invention provides novel means insuring that the pressure of the wiping means upon the margin of the upper shall be relaxed prior to the reverse backward movement of the wiping means, the illustrative construction comprising mechanism for locking the wipers in their foremost position and for releasing them only when they have been lifted to withdraw them from the molded flange. Still another novel feature of this part of the invention consists in means for insuring movement of the wiping means to the proper wiping plane to render it effective in its advancing movement in wiping engagement with the margin of the upper.

A further feature of the invention consists in novel means for gripping the fore-part of an upper and stretching the upper forwardly. Included in this part of the invention are novel gripper closing and operating mechanism, novel gripper locking and releasing mechanism, and novel means affording provision for adjustment of the gripper.

Still other features of the invention are to be recognized in novel mechanism for operating upper forming means under yielding pressure, novel means of support for a former or mold, and a novel arrangement affording provision for ready access to the wiper mechanism for the purpose of inspection or repairs.

The above and other features of the invention, including certain details of construction and combinations of parts, will

now be described with reference to the accompanying drawings and pointed out in the claims.

In the drawings:

5 Fig. 1 is a view in side elevation of a machine in which the different features of the invention are embodied;

10 Fig. 2 is a view in side elevation of mechanism provided for locking and releasing the gripper;

Fig. 3 is a plan view of a portion of the mechanism shown in Fig. 2;

Fig. 4 is a side elevation, with parts in section, of the gripper mechanism;

15 Fig. 5 is a vertical section through the gripper mechanism of Fig. 4, and

Figs. 6 and 7 are views illustrating successive stages in the operation of the upper molding means.

20 Since the features common to the machine herein shown and to prior machines of the illustrative type are fully shown and described in the prior patents mentioned, such features will be referred to herein only 25 as is necessary for an understanding of the present invention.

In order to permit a protracted application of upper forming pressure consistently with economy of time on the part of the operator, the machine is provided with a plurality of sets of instrumentalities for operating respectively on different uppers. It is contemplated that the illustrative machine shall have four such sets of instrumentalities 35 arranged in a row across the machine. As in prior machines, each set of instrumentalities comprises a stationary inner former or mold 2, an outer former 4 comprising a pair of molding members which are advanced 40 and closed about the inner former, and a wiper carrier 6 which is movable forwardly and backwardly along a guideway on the frame of the machine and carries wipers 8 which are operated through toggles 10 to 45 compress the margin of the upper over the inner former 2 after the margin has been wiped inwardly. For operating the different sets of instrumentalities the machine is provided with four identical cams with connections to the outer formers 4 and to the wiper mechanisms, these cams not being shown herein in detail since their construction for the purposes in view is merely a matter of design. The cams are mounted 50 on a horizontal cam shaft 12 supported in bearings in the base of the machine and extending parallel to the front of the machine. Also fast on this shaft is a worm wheel 14 which is rotated by a worm 16 fast on a 55 second shaft 18 extending at right angles to the shaft 12. The shaft 18 is driven by a pulley 20 through a clutch indicated generally at 22. The clutch is actuated to start the machine by means of a treadle 24 extending substantially across the front of the ma-

chine, the treadle being connected by a link 26 to one arm of a clutch controlling lever 28 pivoted at 30 on the frame. The lever 28 has a second arm connected to the clutch and a third arm carrying a roll 32 which is arranged to enter one or another of eight recesses 34 formed in a flange 36 projecting from the worm wheel 14.

It is contemplated that the different sets of formers and wipers shall operate consecutively from right to left of the machine, and when the extreme right hand outer former is back to permit an upper to be placed over the inner former the remaining three sets of outer formers and wipers will be forward in operative position. For the purposes in view the cams for operating the outer formers are so shaped and arranged relatively to the clutch controlling means that operative movement is imparted to each outer former in two successive steps between which the machine comes to rest with the upper only lightly held between the inner and outer formers, as shown in Fig. 6, to permit it to be adjusted relatively to the formers if the operator so desires, and similarly two successive movements are imparted to the outer formers in returning them to starting position. If now the treadle 24 is depressed to actuate the clutch, the first or right hand outer former is moved part way forward to grip the upper lightly round the inner former and the second set of outer formers and wipers is moved part way back, partially releasing the molded upper. It is contemplated that the operator will release the treadle directly after the machine has started to cause the treadle spring (not shown) to operate the lever 28 to open the clutch as soon as the next recess 34 in the flange 36 arrives in position to receive the roll 32. While the machine is thus at rest the operator observes the condition of the work in the first set of formers and if necessary adjusts it relatively to the formers. When the treadle 24 is again depressed, the first outer former is moved fully forward into molding position and the corresponding wipers are operated, and the second outer former is at the same time moved fully back so that the molded upper may be removed and an unmolded upper placed in position. When the treadle is again depressed the second outer former is again moved part way forward and the third part way back, whereupon the machine again comes to a stop. Upon subsequent depressions of the treadle the second and third sets of formers continue to operate in unison, the third and fourth operate together, and finally the fourth and the first. By this arrangement each set of outer formers and wipers is moved forward and backward in four stages during half a revolution of the cam shaft and is stationary in molding position dur-

ing half a revolution of the shaft, being unaffected by four consecutive treadlings.

To provide a firm support for each inner former or mold 2 against the downward pressure of the wipers, there is associated with each of said formers a strut 38 pivoted at 40 on the frame of the machine and arranged to be moved forwardly into supporting position under a depending lug 42 on the 10 inner former by means of a spring plunger 44 which bears against the rear face of the strut. The strut 38 has formed upon it a lug 46 which, when the strut is in operative position, engages a stop screw 48 on the 15 frame. When the outer former and the wipers are in their inoperative position, the strut 38 is swung backwardly to its inoperative position, as shown in Fig. 1, by means of a pin 50 fixed in the end of an arm 52 of 20 a cam operated lever 54 through which operative movement is imparted to the outer former. When the lever 54 is operated to move the outer former backwardly away from the inner former, the pin 50 engages 25 the lug 46 and swings the strut 38 about its pivot into inoperative position where it is held to permit free access to the inner former in positioning the work. As the outer former receives its forward movement, the 30 pin 50 releases the strut and permits it to be swung forwardly into operative position by its spring plunger 44.

Each gripper for drawing the upper forwardly about the associated inner former 2 35 comprises (Figs. 4 and 5) a fixed jaw 56 formed on the lower end of a member 58 which is mounted for swinging movement on a pivot 60 fixed in a slide 62 adjustably movable upwardly and downwardly along a 40 bracket 64 on the frame of the machine. The member 58 is adjusted about its pivot for different lengths of upper by means of a thumb screw 66 which is threaded through a lug on the member 58 and bears at its inner 45 end against a cap 68 on the frame. The end of the screw is held in engagement with the cap by a spring plunger 70 which is mounted in the slide 62 and bears against a projection on the member 58. Pivoted at 72 on the 50 member 58 is a co-operating gripper jaw 74 which has an arm 76 extending upwardly within a recess in the member 58 and provided with a slot to receive the end of one arm 78 of a bell crank lever 80 which is 55 mounted on the pivot 60. The other arm 82 of the bell crank lever 80 has a rounded end which enters a slot formed in a rack slide 84 movable in the slide 62 in parallel relation to the direction of adjusting movement 60 of the latter. It will be evident that downward movement of the rack slide 84 operates through the bell crank lever 80 first to impart closing movement to the gripper jaw 74 and then, against the resistance encountered by the jaws, to swing them with the

member 58 about the pivot 60 to pull and stretch the upper forwardly. Subsequently the gripper is swung reversely to starting position by the spring plunger 70 until the screw 66 engages the cap 68, opening movement being imparted to the pivoted jaw 74 by means of a spring plunger 86 which is mounted in the arm 78 and engages the member 58.

The rack slide 84 is moved downwardly 75 to operate the gripper by means of a pinion 88 which is fast on a horizontal shaft 90 supported by the bracket 64. Also fast on the shaft 90 (Fig. 4) is a worm wheel 92 meshing with a worm 94 rotatably mounted in a 80 lever 96 which is loosely pivoted on the shaft 90. By movement of the lever 96, through mechanism to be hereinafter described, the pinion 88 is thus turned through the connections including the worm 94 and the worm 85 wheel 92 to operate the gripper.

The slide 62 is normally locked to the bracket 64 against downward movement by means of a roll 98 which is mounted in a recess in the cap 68, this roll being normally 90 held in engagement with a wedge face 100 of said recess and a face 102 on the slide 62 by means of a spring plunger 104 in the cap 68. It will thus be understood that by wedging action of the roll between the relatively 95 inclined faces 100 and 102 the slide 62 is normally restrained from downward movement. The roll may be moved out of its locking position by a pin 106 mounted in the cap 68 on the opposite side of the roll from 100 the spring plunger 104, the pin being operated by an eccentric 108 having a handle 110 by which it may be turned. When the slide 62 is thus unlocked, the slide and the gripper may be moved along the bracket 64 to 105 adjust the gripper heightwise of the upper. Upward movement of the slide is effected through the rack 84 and the pinion 88 by rotation of the worm 94 through turning movement of a hand wheel 111 on the worm shaft, 110 the lever 96 being held stationary by its operating connections hereinafter described. Similarly, by reverse movement of the worm, the slide 62 may be permitted to move downwardly along the bracket. 115

The lever 96 is connected by a link 112 to one arm 114 (Fig. 2) of a three armed lever 116 pivoted on a shaft 118 on the frame. A second arm 120 of this lever is connected by a link 122 to a treadle 124 pivoted on the 120 same shaft as the clutch treadle. Depression of the treadle 124 first closes the gripper and then swings it about the pivot 60 to stretch the upper, as hereinbefore described. The third arm 126 of the lever 116 125 has an edge concentric with the pivot of the lever, on which are formed ratchet teeth 128 engaged by a pawl 130 which is pivoted on the frame and is held by a spring plunger 132 normally in engagement with the teeth. 130

The pawl and ratchet mechanism thus locks the gripper in any position to which it is moved in pulling an upper.

The machine is provided with means whereby the pawl 130 may be disengaged from the ratchet teeth at any time to release the gripper, and also with means whereby the pawl is automatically disengaged as the outer former is moved back to inoperative position. For disengaging the pawl manually the arm 126 of the lever 116 has slidingly mounted upon it a member 134 having a face 136 concentric with the pivot of the lever and arranged to engage the pawl 130 and push it away from the ratchet teeth. Pivoted on the member 134 is a block 138 positioned in a groove 140 formed in one arm of a lever 142 pivoted at 144 on the arm 126. The other arm of the lever 142 is connected by a link 146 to a small treadle 148 pivoted on the gripper operating treadle 124. The treadle 148 is normally raised by a spring plunger which is mounted therein and bears against a projection on the treadle 124. Depression of the treadle 148 serves to turn the lever 142 about its pivot 144 and through the groove and block connection 140 and 138 to slide the member 134 along the arm 126 until its concentric face 136 engages the pawl 130 and pushes it away from the ratchet teeth 128. The pawl is automatically disengaged from the teeth in the return of the outer former to starting position by a detent 150 pivoted on a link 152 which connects the outer former cam lever 54 with the former operating toggle links 154 and 156. The detent has a projection normally held against a stop pin 160 by means of a spring plunger 162 mounted in a lug on the link, the spring plunger permitting the detent to ride over the projection 158 in the operative upward movement of the link.

45. To provide for yield in the advancing and closing movement of each outer former 4 a spring 164 is housed in the frame of the machine and bears at one end against the end of the housing and at the other end 50 against a collar 166 having a bearing in the bored end of the housing and adjustably mounted on a rod 168 which passes through the spring and the housing. A nut and a lock nut 170 are screwed on the rod 168 55 for adjusting the collar 166 and thereby varying the pressure of the spring. On the opposite end of the rod is pivoted at one end a lever 172 which at its opposite end is connected to the outer former carriage 60 174, and pivoted on this lever between its ends is one end of the toggle link 154 through which the outer former is operated. Straightening of the toggle 154, 156 serves first to swing the lever 172 about its pivot 65 on the rod 168 and thus to advance the

outer former to operative position, and after the former has firmly engaged the upper further movement of the toggle is taken up by the turning of the lever 172 about its connection to the carriage 174 against 70 the pressure of the spring 164. Insurance is thus afforded that every upper shall be operated upon with firm molding pressure, and the arrangement of the operating mechanism, moreover, is such as to afford ready, 75 access to the operating parts.

Each of the wiper carriers 6 is advanced to operative position and its wipers are subsequently forced downward to compress the flange of the upper through a single operating means comprising a three armed lever 176 on the wiper carrier, the lower arm 178 of which is connected by a link 180 to a lever 182 connected in turn by a link 184 to a swinging frame 186 in operative engagement with the wiper cam. As in prior machines, the lever 176 is so controlled that the wipers, after their advancing and closing movement, are forced downwardly to compress the margin of the upper by the operation of the toggles 10 through a link 188 which connects the toggles to the lever arm 178. In the present machine insurance is afforded that the wipers shall be partially depressed to bring them to the proper overwiping plane before they engage the margin of the upper. For this purpose, a rearwardly extended arm 190 of the lever 176 carries a roll 192 which, as the wipers begin to move forwardly, engages a face 194 of 90 a switch cam 196 pivoted at 198 in a recess in the frame of the machine. The lever 176 is thus operated partially to straighten the toggles 10 and depress the wipers to operative position, and the roll 192 then travels 100 underneath the switch cam and along a guiding ledge 200 on the frame to prevent further depression of the wipers during their overwiping movement. When the roll 192 passes beyond the end of the ledge 200 the 110 toggles are further straightened by the turning of the lever 176 to cause the wipers to compress the flange of the upper. At the end of the forward movement of the wipers a block 202 on the wiper carrier 6 rides 115 over a locking pawl 204 which is pivoted on the frame of the machine and is held upward against a stop by a spring plunger 206. This locking means insures that upon reverse movement of the wiper operating mechanism the wipers shall be held against rearward movement until they have been 120 fully elevated above the margin of the upper by the flexing of the toggles. For unlocking the wiper carrier at this point the lever 176 has a forwardly extending arm 208 which engages and depresses the pawl 204 when the wipers have been fully raised and the roll 192 has been elevated into alignment 125 with the upper face of the switch cam 196. 130

During the backward movement of the wiper carrier the roll 192 travels along a guiding ledge 210 above the switch cam and near the end of this movement depresses the cam which is immediately returned to its uppermost position by the action of a spring 212.

To facilitate replacement of parts, each of the wiper carriers 6 is provided with a 10 semi-circular bearing 214, and co-operating bearings 216 are formed on the frame of the machine to receive a fulcrum bar. In the use of this mechanism the wiper carrier is disconnected from its operating mechanism, as by removal of a pin 218, and is moved along its guideway to bring its bearing 214 into alignment with the bearings 216 on the frame. A bar is then placed in the bearings 216 and the wiper carrier is turned 20 up on the bar to expose the wiper plates. This affords convenient means for getting at the wipers and obviates the necessity of lifting the heavy carrier from the machine.

Having described the invention, what we 25 claim as new and desire to secure by Letters Patent of the United States is:

1. In an upper shaping machine, the combination with inner and outer formers relatively movable to shape an upper between 30 them, of power driven means for effecting relative upper shaping movement of said formers in successive steps with a pause in the operation of the machine between said steps to permit adjustment of the upper 35 prior to the application of the final upper shaping pressure.

2. In an upper shaping machine, the combination with an inner former, of an outer former movable to embrace and clamp the 40 end portion of an upper round the periphery of the inner former, power driven means for imparting operative movement to said outer former, and controlling means automatically operative to bring said outer 45 former to a stop with the upper lightly held between it and the inner former and manually operative subsequently to cause said outer former to complete its upper clamping movement.

50 3. In an upper shaping machine, the combination with inner and outer molds and power operated mechanism for effecting relative upper shaping movement of said molds, of controlling mechanism for bringing the machine to a stop with the upper 55 lightly held between said molds to permit adjustment of the upper prior to the application of the full molding pressure.

4. In an upper shaping machine, the combination with inner and outer molds and power operated mechanism for effecting relative upper shaping movement of said molds, of controlling mechanism automatically operative to stop said relative movement of the molds with the molds in en-

gagement with the upper and before the upper is subjected to the final molding pressure, said controlling mechanism being manually operative subsequently to cause the power mechanism to complete said relative 70 upper shaping movement of the molds.

5. In an upper shaping machine, the combination with inner and outer formers relatively movable to shape the end portion of an upper between them, of power driven 75 means for effecting relative upper shaping movement of said formers, and controlling mechanism enabling the operator to determine for each upper the time interval between the beginning of relative power movement of the formers and the final application of the upper shaping pressure.

6. In an upper shaping machine, the combination with inner and outer formers relatively movable to shape an upper between 85 them, and means for flanging the margin of the upper projecting from between said formers, of power operated means for effecting relative upper shaping movement of said formers, and means for controlling the 90 power effected relative movement of the formers constructed to permit inspection of the upper and adjustment of the upper relatively to the formers subsequently to their power effected engagement with the upper 95 and prior to the operation of the upper flanging means.

7. In an upper shaping machine, the combination with inner and outer formers relatively movable to shape the end portion of 100 an upper between them, and power operated means for flanging the margin of the upper projecting from between said formers, of operating and controlling means enabling the operator to determine for each upper the 105 time interval between the beginning of relative power movement of the formers and the beginning of the upper flanging operation.

8. In an upper shaping machine, the combination with inner and outer formers constructed and arranged to shape the end portion of an upper between them, and power operated means for flanging the margin of the upper projecting from between said 110 formers, of power means for effecting relative upper shaping movement of said formers to clamp the upper lightly while permitting it to be adjusted relatively to the formers and to apply subsequently at a time determined by the operator the full upper 115 shaping pressure.

9. In an upper shaping machine, the combination with inner and outer formers relatively movable to shape an end portion of an upper between them, and power driven 125 means for flanging the margin of the upper projecting from between said formers, of power driven means for effecting relative upper shaping movement of the formers, and means for controlling said power effected rel- 130

ative movement of the formers constructed to permit adjustment of the upper relatively to the formers subsequently to their power effected engagement with the upper 5 and prior to the operation of the upper flanging means.

10. In an upper shaping machine, the combination with inner and outer molds relatively movable to mold the end portion of an upper between them, and power operated wipers for wiping the margin of the upper inwardly over the inner mold, of power operated mechanism for effecting relative operative movement of said molds, and 15 controlling mechanism automatically operative to stop said relative movement of the molds with the molds engaging the upper with comparatively light pressure and manually operative subsequently to cause the power mechanism to complete said relative movement of the molds to subject the upper to the full molding pressure.

11. In an upper shaping machine, the combination with an inner mold, an outer mold for embracing and clamping an end portion of an upper round the periphery of the inner mold, and power operated wipers for wiping the margin of the upper inwardly over the inner mold, of power driven means 25 for imparting upper clamping movement to the outer mold, and controlling mechanism for bringing the machine to a stop with the upper lightly held between the inner and outer molds to permit adjustment of the upper relatively to the molds prior to the application of the full molding pressure.

12. In a machine of the class described, the combination with means for embracing and clamping the heel end portion of an upper, of power driven means for operating said upper clamping means, and controlling mechanism automatically operative to bring the machine to a stop with the upper lightly held by said clamping means to permit its 45 adjustment relatively to said means, said controlling mechanism being manually operative subsequently to cause the power means to complete the operative movement of the upper clamping means.

13. In a machine of the class described, the combination with wiping means for forming a flange on the margin of an upper, of a single operating means through which said wiping means is moved reversely after the flange forming operation both in a direction transverse to the plane of said flange and in a direction substantially parallel to said plane, and controlling mechanism automatically operative to insure a movement of the wiping means in a direction transverse to said plane to relax the pressure on the flange prior to movement of the wiping means parallel to said plane.

14. In a machine of the class described, the combination with wiping means for

forming a flange on the margin of an upper, of operating means for moving said wiping means reversely from over said flange after the flange forming operation, mechanism automatically operative in response to resistance to such reverse movement of the wiping means for moving said means in a direction transverse to the plane of said flange to relax the pressure on the flange, and retaining means for holding said wiping means against said reverse movement until after it has been moved in a direction transverse to said plane to relax the pressure on the flange.

15. In a machine of the class described, the combination with wiping means for forming a flange on the margin of an upper, of operating means for moving said wiping means reversely from over said flange after the flange forming operation, mechanism automatically operative in response to resistance to such reverse movement of the wiping means for moving said means in a direction transverse to the plane of said flange to relax the pressure on the flange, a retaining device for holding the wiping means against said reverse movement, and mechanism automatically operative to release said wiping means only after it has been moved in a direction transverse to said plane to relax the pressure on the flange.

16. In a machine of the class described, the combination with wiping means for forming a flange on the margin of an upper, of operating means for moving said wiping means reversely lengthwise of the upper after the flange forming operation, mechanism connected to said operating means to be operated in response to resistance to such reverse movement of the wiping means for moving said wiping means in a direction transverse to the plane of said flange to relax the pressure on the flange, and means for resisting such reverse movement of the wiping means and for releasing said means only after the pressure on the flange has been relaxed.

17. In a machine of the class described, the combination with wiping means for forming a flange on the margin of an upper, of operating means for moving said wiping means reversely lengthwise of the upper after the flange forming operation, mechanism connected to said operating means to be operated in response to resistance to such reverse movement of the wiping means for moving said wiping means in a direction transverse to the plane of said flange to relax the pressure on the flange, a device automatically operative to hold the wiping means against reverse movement, and mechanism connected to said operating means for causing said device to release the wiping means after the pressure on the flange has been relaxed.

18. In a machine of the class described, the combination with wiping means for forming a flange on the margin of an upper, and operating means comprising a member movable in one direction to advance the wiping means and then to depress the wiping means to compress the flange of the upper and in the reverse direction to lift the wiping means and to retract it from over said flange, of mechanism automatically operative to insure lifting movement of the wiping means prior to its retracting movement.

19. In a machine of the class described, the combination with end embracing wipers for forming a flange on the margin of an upper, of operating means for moving said wipers reversely lengthwise of the upper after the flange forming operation, mechanism automatically operative in response to resistance to such reverse movement of the wipers to move them in a direction transverse to the plane of said flange to relax the pressure on the flange, and retaining mechanism automatically operative to prevent such reverse movement of the wipers until after they have been moved to relax the pressure on the flange.

20. In a machine of the class described, the combination with end embracing wipers for forming a flange on the margin of an upper, of a wiper carrier movable to advance and to retract said wipers, operating means for advancing and retracting said carrier, means on said carrier connected to said operating means to be operated in response to resistance to retracting movement of the carrier for moving said wipers in a direction transverse to the plane of said flange to relax the pressure on the flange, a device automatically operative to lock said carrier in its advanced position, and mechanism constructed and arranged to unlock said carrier only after the wipers have been moved to relax the pressure on the flange.

21. In a machine of the class described, the combination with end embracing wipers, a wiper carrier movable to advance said wipers for forming a flange on the margin of an upper and relatively to which the wipers are movable to compress said flange, and operating mechanism comprising a member movable in one direction to advance said carrier and then to impart compressing movement to the wipers and in the reverse direction to move the wipers relatively to the carrier to relax the pressure on the flange and to withdraw the carrier, of mechanism automatically operative to hold said carrier in its advanced position and to release it only after the wipers have been moved through said member to relax the pressure on the flange.

22. In a machine of the class described, the combination with end embracing wipers,

a wiper carrier movable to advance said wipers for forming a flange on the margin of an upper and relatively to which the wipers are movable to compress said flange, and operating mechanism comprising a member movable in one direction to advance said carrier and then to impart compressing movement to the wipers and in the reverse direction to move the wipers relatively to the carrier to relax the pressure on the flange and to withdraw the carrier, of a retaining device for holding the carrier in its advanced position, and a member operative in time relation to said operating member to cause said retaining device to release the carrier after the wipers have been moved to relax their pressure on the flange.

23. In a machine of the class described, the combination with end embracing wipers, a wiper carrier movable to advance said wipers for forming a flange on the margin of an upper and to retract the wipers, toggle means on said carrier for moving the wipers to compress said flange, and a lever on the carrier operatively connected to said toggle means and through which also advancing and retracting movements are imparted to the carrier, of mechanism automatically operative to hold said carrier against retracting movement until after said toggle means has been operated through the lever to relax the pressure of the wipers on said flange.

24. In a machine of the class described, the combination with end embracing wipers, a wiper carrier movable to advance said wipers for forming a flange on the margin of an upper and to retract the wipers, toggle means on said carrier for moving the wipers to compress said flange, and a lever on the carrier operatively connected to said toggle means and through which also advancing and retracting movements are imparted to the carrier, of a latch automatically operative to lock said carrier in advanced position, and a member connected to said lever for operating said latch to release the carrier after said toggle means has been operated through the lever to relax the pressure of the wipers on said flange.

25. In a machine of the class described, the combination with wiping means for forming a flange on the margin of an upper, and a single operating means through which said wiping means is advanced and retracted and through which it is also moved in different directions alternately to compress said flange and then to release the pressure on the flange, of mechanism automatically operative to insure a movement of the wiping means in the direction of compression to bring it to the proper wiping plane before it becomes effective in wiping engagement with the margin of the upper.

26. In a machine of the class described,

the combination with wiping means for forming a flange on the margin of an upper, of a single operating means through which said wiping means is advanced and retracted 5 and through which it is also moved in different directions alternately to compress said flange and then to release the pressure on the flange, of a cam device automatically operative in the initial portion of the advancing 10 movement of the wiping means to impart to said means a movement in the direction of compression to bring it to the proper wiping plane.

27. In a machine of the class described, 15 the combination with end embracing wipers, and operating means comprising a member movable in one direction to impart successively advancing and compressing movements to said wipers and in the opposite direction to impart to the wipers withdrawing movements in the reverse order, of a device automatically operative in the advancing movement of said wipers to move them 20 in the direction of compression a sufficient 25 distance to bring them to the proper wiping plane before they become effective on the margin of the upper.

28. In a machine of the class described, the combination with end embracing wipers, and 30 operating mechanism comprising a member through which said wipers are advanced and are subsequently moved in a direction to compress the margin of the upper, of a controlling member movable with said operating 35 member, a guide co-operating with said controlling member to prevent compressing movement of the wipers until their advancing movement has been substantially completed, and a device arranged to act on said 40 controlling member to force it toward said guide in the initial portion of the advancing movement of the wipers to bring the wipers to the proper wiping plane.

29. In a machine of the class described, 45 the combination with end embracing wipers, and a wiper carrier movable to advance and retract said wipers and relatively to which the wipers are movable in a different direction to compress the margin of the upper, of 50 a lever arm pivoted on said wiper carrier and connected to the wipers for imparting to them their compressing movement, means arranged to operate through said lever arm also to advance the wiper carrier, a controlling 55 member movable with said lever arm, a guide co-operating with said controlling member to prevent compressing movement of the wipers until after their advancing movement has been substantially completed, 60 and a cam member arranged to act on said controlling member in the advancing movement of the wipers to force said controlling member toward the guide to bring the wipers to the proper wiping plane.

30. In a machine of the class described,

the combination with end embracing wipers, and a wiper carrier movable to advance and retract said wipers and relatively to which the wipers are movable alternately to compress the margin of the upper and to release 70 the pressure on said margin, of an operating member pivoted on said wiper carrier and connected to the wipers for imparting to them their pressure applying and pressure releasing movements, means arranged to operate through said member to advance and retract the wiper carrier, a controlling member mounted for swinging movement with said operating member, spaced guides for limiting the swinging movements of said 80 controlling member in opposite directions, and a cam device automatically operative in the advancing movement of the wiper carrier to swing said controlling member toward one of said guides to bring the wipers 85 to the proper wiping plane, said device being yieldable in the retracting movement of the wipers to permit said controlling member to return to its initial position.

31. In a machine of the class described, 90 the combination with inner and outer formers for molding the end portion of an upper between them, means for wiping the margin of the upper over the inner former, and operating mechanism for advancing and then 95 depressing said wiping means and for subsequently raising said means and returning it to its starting position, of mechanism automatically operative in time relation to the advancing movement of said wiping 100 means to insure partial depression of said means prior to the conclusion of its advancing movement.

32. In a machine of the class described, the combination with upper positioning means, of a gripper for engaging the forepart of the upper and pulling it forwardly, 105 said gripper comprising relatively movable jaws, a support for said jaws movable lengthwise of the upper, a pivotally mounted lever, and mechanism arranged to operate through said lever first to effect relative closing movement of said jaws and then to move said gripper support to cause the gripper to pull the upper.

33. In a machine of the class described, the combination with upper positioning means, of a gripper for engaging the forepart of the upper and pulling it forwardly, 110 said gripper comprising relatively movable jaws, a support for said jaws mounted for swinging movement lengthwise of the upper, a bell crank lever having an arm connected to one of the gripper jaws, and mechanism connected to the other arm of said bell 115 crank lever for operating through the lever to effect relative closing movement of the jaws and then to swing the gripper support in a direction to cause the gripper to pull the upper.

34. In a machine of the class described, the combination with upper positioning means, of a gripper for engaging the forepart of the upper and pulling it forwardly, 5 said gripper comprising relatively movable jaws, a support for said jaws mounted for swinging movement lengthwise of the upper, a bell crank lever having an arm arranged to effect relative closing movement of said 10 jaws, and rack and pinion mechanism connected to the other arm of said bell crank lever for operating through said lever to close the gripper on the upper and then to move the gripper support to cause the gripper to pull the upper.
35. In a machine of the class described, the combination with upper positioning means, of a gripper for engaging the forepart of the upper and pulling it lengthwise, 20 means for operating said gripper, a device automatically operative to hold said gripper in any position to which it is moved by its operating means, power operated mechanism to cause said holding device subsequently to release the gripper, and additional mechanism permitting manual release of the gripper at the will of the operator.
36. In a machine of the class described, the combination with upper positioning 30 means, of a gripper for engaging the forepart of the upper and pulling it lengthwise, treadle means for operating said gripper to pull the upper, a device automatically operative to hold the gripper in any position to which it is moved by said treadle means, and auxiliary treadle means arranged to be operated by the same foot of the operator to cause said holding device to release the gripper.
37. In a machine of the class described, the combination with forming means for the heel end portion of an upper and power driven mechanism for operating said forming means, of a gripper for engaging the forepart of the upper and pulling it lengthwise, 45 a device automatically operative to lock said gripper in any position to which it is moved to pull the upper, and power means automatically operative subsequently to cause said locking device to release the gripper.
38. In a machine of the class described, the combination with upper positioning means, of a gripper for engaging the forepart of the upper and pulling it lengthwise, 55 and operating mechanism for imparting upper pulling movement to said gripper, said operating mechanism comprising parts relatively movable to adjust the gripper heightwise of the upper.
39. In a machine of the class described, the combination with upper positioning means, of a gripper for engaging the forepart of the upper and pulling it lengthwise, 60 a support for said gripper mounted for adjusting movement heightwise of the upper, a device for locking said support in adjusted position, and operating means comprising rack and pinion mechanism for imparting upper pulling movement to said gripper, 70 said operating means including parts relatively movable to impart through said rack and pinion mechanism adjusting movement to said gripper support.
40. In a machine of the class described, 75 the combination with inner and outer formers relatively movable to shape the end portion of an upper between them, of operating mechanism comprising a lever connected to one of said formers and extending in approximately perpendicular relation to the direction of movement of said former, a pivotal support for said lever, and controlling means for said support arranged to yield upon the application of a determinate degree 80 of pressure to the upper.
41. In a machine of the class described, the combination with a former for the end portion of an upper, of a lever connected at one end to said former, a pivotal support 90 for the other end of said lever, means connected to the lever between its ends for operating it, and controlling means from said lever support arranged to yield upon the application of a determinate degree of 95 pressure to the upper.
42. In a machine of the class described, the combination with a former for the end portion of an upper, of a lever connected to said former for operating it, a toggle for 100 operating said lever, a pivotal support for the lever, and controlling means for said support arranged to yield upon the application of a determinate degree of forming pressure to the upper.
43. In a machine of the class described, 105 the combination with a former for shaping the end portion of an upper, and means for compressing the marginal portion of the upper over said former, of a support for 110 said former arranged to be maintained normally in inoperative position to afford access to the former in positioning the work, and power means automatically operative to cause said support to move to its operative position.
44. In a machine of the class described, the combination with inner and outer formers for molding the end portion of an upper between them, and means for flanging the 115 margin of the upper over said inner former, of a support for said inner former, and power operated means for maintaining said support normally in inoperative position and automatically operative after the starting of the machine to cause said support to move to its operative position.
45. In a machine of the class described, 120 the combination with inner and outer formers for molding an end portion of an 125 upper.

upper between them, and means for flanging the margin of the upper over said inner former, of a strut for supporting said inner former against the upper flanging pressure, 5 said strut being movable into and out of operative position, spring means for moving said strut to operative position, and a power controlled member for holding said strut normally in inoperative position and 10 for releasing it after the starting of the machine to permit it to move to its operative position.

46. In a machine of the class described, the combination with a frame having a bearing adapted to support a fulcrum bar, of a wiper carrier operatively movable on said frame and provided with a bearing movable into substantial alinement with said supporting bearing to permit said wiper carrier to be turned about the fulcrum bar to 20 facilitate inspection and repairs.

47. In a machine of the class described, the combination with a frame, of a wiper carrier on said frame, said frame and carrier having bearing portions relatively movable into substantial alinement and adapted to receive a fulcrum bar about which the wiper carrier may be turned to facilitate inspection and repairs.

30 48. In an upper shaping machine, the

combination with means for clamping the heel end portion of an upper about a form, of power operated means for effecting relative movement of said clamping means and the form in successive steps to position 35 them in co-operative clamping relation with a pause in the operation of the machine between said steps prior to the application of the full clamping pressure to permit the upper to be adjusted relatively to the form. 40

49. In an upper shaping machine, the combination with means for clamping the heel end portion of an upper about a form, of power operated means for effecting relative movement of said clamping means and the form to clamp the upper and controlling mechanism automatically operative to bring the machine to a stop after power effected relative movement of said clamping means and the form substantially into co-operative 50 relation and while the upper may be readily slipped about the form to permit adjustment of the upper relatively to the form prior to the application of the full clamping pressure.

55 In testimony whereof we have signed our names to this specification.

JOSEPH GOULBOURN.
FRED RICKS.
